UNITED STATES PATENT OFFICE.

JEAN H. MARSHALL, OF BINGHAMTON, NEW YORK.

SURGICAL APPLIANCE.

Application filed July 5, 1922. Serial No. 572,941.

To all whom it may concern:

Be it known that I, JEAN H. MARSHALL, a citizen of the United States, residing at Binghamton, in the county of Broome and

5 State of New York, have invented certain new and useful Improvements in Surgical Appliances, of which the following is a specification.

This invention relates to surgical appliances, and is particularly suited for embodiment in appliances for assisting copulation and promoting the attainment of resultant fecundation.

Various forms of appliances have heretofore been devised for corresponding purposes, and some of such prior appliances are said to have been used in numerous instances with admittedly beneficial results. In all of the prior forms of such appliances 20 with which I am acquainted, disadvantageous features have been apparent, prominent among which have been the enclosure of a major portion of the male organ and the presence of metallic or other relatively harsh substances liable to cause contusions or 25 lacerations of the mucous membrane of the genitalia of users.

It is well recognized that effective copulation depends upon confidence as well as upon ability to cause suitable penetration and to supply adequate fullness or caliber, so as to afford the needed stimulation of excitement and elation.

Confidence is not compatible with a fear 35 of injury, hence such a fear may more than offset the effect of other features of such appliances which might otherwise prove beneficial; and normal stimulation is impeded when a considerable portion of the length 40 of penetration is completely enclosed.

Inability to cause penetration for a normal distance and of suitable caliber sometimes results from physical deformities, but more frequently first results from sub-normal 45 development or from a nervous or physical condition of a temporary or transitory nature. When realized by the victim, such inability causes a loss of confidence which becomes chronic, even after recovery from the first cause. During the continuance of such inability, attempted copulation causes increasing loss of confidence and added aversion of both parties, not infrequently leading to infelicity and ultimate separation 55 which could have been avoided had proper and timely treatment been applied.

It is an object of this invention to provide an appliance which will suitably supplement and assist the penetrative power of a male genital organ. 60

Another object is to provide an appliance of such form as to enable it to suitably supplement the caliber of such an organ during copulation.

Another object is to provide such an appliance which is so constructed and arranged that there will be no harsh materials likely to be brought in contact with delicate mucous membrane surfaces of either of the parties to its use, to the end that there will 70 be neither real nor imaginary cause for apprehension of injury therefrom.

Another object is to provide such an appliance which is so constructed and arranged that it may be thoroughly cleansed 75 after use, and so that infection of delicate surfaces therefrom may be completely avoided.

A further object is to provide such an appliance with facilities for quickly and inconspicuously adjusting it for use and removing it from the body of the wearer. 80

Other objects and aims of this invention, more or less specific than those just referred to, will be in part obvious and in part 85 specifically set forth in the following specification and more fully pointed out in the claims.

This invention consists of certain features of construction, combination and arrangement of parts which are illustratively shown in the annexed drawing, in which like characters of reference denote the same parts through all views; of which— 90

Figure 1 is a perspective view of an appliance embodying this invention. 95

Figs. 2, 3, 4, 5 and 6 are fragmentary views of details to be referred to.

Referring to the drawing,—the splint A comprises a core 21, which is enclosed in soft 100 elastic material 22 having a non-hygroscopic outer coating 23. The general outline of the core 21 is indicated by dotted lines in Fig. 1, and such core may consist of a hollow metallic tube as indicated by the fragmentary 105 views thereof in Figs. 2 and 5.

It is believed that best results will be obtained if the material 22 has a low coefficient of heat conduction, so that it will not impart a cold sensation to the touch; and the 110 thickness and character of this material should be such as to prevent injury to deli-

cate body surfaces with which it may be brought in contact. For the accomplishment of this purpose in a convenient and relatively inexpensive manner, the material 5 22 should be sponge rubber or the like; and, in order to minimize opportunity for harboring infection, such material should be molded directly upon the core 21.

As an example of an alternative construction which would fall within the general scope of this invention, it may be stated that the entire splint A may be made of a single mass of rubber, the inner portion of which (corresponding in a general way with the 10 core 21) being made of relatively hard rubber (either solid or hollow as desired); such inner portion being molded and vulcanized integral with an outer spongy or cushioning portion corresponding with the material 22.

15 Said splint, as a whole, should have form and rigidity such as to enable it to suitably supplement the caliber of and support a male genital organ during copulation. Inasmuch as the cushioning material 22 should 20 be of some relatively soft and yielding substance, the inner portion or core should be of form and rigidity such as to suitably reinforce the splint.

When sponge rubber or other correspondingly porous substance is employed for material 22,—it is very desirable, for hygienic reasons, that the pores thereof should be protected by a non-hygroscopic covering. Such covering may consist of an outer finish or a 30 suitable coating formed integral with or applied directly to the outer surface of the material 22; however, best results and the greatest degree of hygienic safety will be promoted by the employment of an envelope 35 which is preferably of non-absorbive and elastic material—such, for example, as thin sheet rubber—of form and thickness enabling it to be readily placed upon or removed from the material 22, to the end that 40 such an envelope may be removed after each use for careful examination and cleansing, and can be readily and inexpensively replaced whenever it shows signs of deterioration.

45 The member B serves as a support for the splint A, and said member is of such form as to enable it to embrace a male genital organ near the base thereof and to conform to adjacent abdominal and pelvic contour.

50 The tenons 31 carried by the splint A and the tenons 32 carried by the member B are formed and arranged to so interlock as to provide means for detachably securing said splint to said member, as hereinafter more 55 fully explained.

The member B comprises a ring-like body 33, having an opening 34 therethrough for receiving a male genital organ, and the piece 35 which is adjustable relatively to the body 60 33 for the purpose of varying the effective

size of the opening 34. A block 36 (see Figs. 2 and 5) is molded in the material of the body 33, and the sides of the projecting portion of said block have V-grooves formed therein for so engaging the rear side of the 70 slide 37 as to permit movement of said slide transversely of the opening 34.

The piece 35 is forced fit over the slide 37, and said slide has a slot 38 formed therein through which the screw 39 may be inserted 75 in a threaded hole provided therefor in the block 36; the head of said screw being so formed as to be adapted to bear upon the portions of the front of the slide 37 at either side of the slot 38 for the purpose of locking the piece 35 against changes in its adjustment relative to the body 33.

The tenons 31 are formed integral with the stud 40, and said stud is securely fixed in the end of the core 21. The relative formation 80 of the material 22 of the splint A and of the piece 35 of the member B is such that the tenons 31 and 32 will be suitably enclosed by said material when said splint is secured to said member.

85 A latch-piece 41 is provided for securing the tenons 31 and 32 in engaging relation; said piece being carried at one end of the flexible strip 42 (see Figs. 4, 5 and 6) and the other end of said strip being secured to the stud 40.

90 The space between the right-hand pair of the tenons 32 (as viewed in Fig. 3) and that between the left-hand pair of the tenons 31 (as viewed in Fig. 4) is such as to freely receive the latch-piece 41. It is, therefore, evident that when the respective tenons of said pieces are disposed in alignment, as shown in Fig. 6, the latch-piece 41 may be disposed partly in the space between such tenons 31 95 and partly between such tenons 32 so as to lock them against relative movement.

95 The resiliency of the strip 42, of the material 22 adjacent said strip, or of both said strip and material, is so applied as to tend 100 to carry the latch-piece 41 to the position in which it may lock the tenons 31 and 32 against relative movement, as just described; and said strip 42 is of such form and so disposed within the material 22 of the splint A that pressure upon the outside of said splint in the region of said strip will move said latch-piece 41 to a position where it will not so lock said tenons.

105 The belt 51 is connected to the annular member B by the straps 52 and 53, which serve as means of securing said member to the body of a wearer; the use of such securing means being particularly advantageous when said annular member is to be worn 110 other than during the use of the splint A. Under other conditions of use of the splint A and member B, the securing means comprising the belt 51 and straps 52 and 53 may 115 be dispensed with.

The operation of the appliance shown by the drawing and hereinbefore described in detail is as follows:

- When it is desired to vary the effective size of the orifice in the member B so as to fit the intended organ of a given person,—the screw 39 should be loosened sufficiently to permit the piece 35 to be moved under the head thereof, and said piece should then be moved transversely of the opening 34 until the effective size thereof is such that, when said member occupies its intended position at the base of such organ, the walls of said opening will snugly embrace such organ.
- When it is desired to secure the member B in position upon the person prior to the application thereto of the splint A,—said member should be placed over the organ, with the piece 35 on the side of said member away from the body of the wearer and below the organ, and said member should then be secured in position by means of the straps 52 and 53 and the belt 51; said straps passing one side and the other of the scrotum and being adjusted as to length so as to hold said member in desired position.

When the member B has been secured in position, as just described, the splint A may be secured to said member by applying the upper pair of the tenons 31 directly above the upper pair of the tenons 32 (thus bringing the lower pair of the tenons 31 between the upper and lower pairs of the tenons 32) and thereupon sliding the end of said splint downwardly with reference to said member, and meanwhile pressing upon the outer surface of said splint in the region of the strip 42 so as to move the piece 41 out of the path of the tenons 32. When the tenons 31 have thus been brought into alignment with the tenons 32,—the pressure upon the side of the splint A should be removed, thus permitting the latch-piece 41 to move into locking engagement with said tenons.

The splint A will thereupon be held securely in a position parallel to and below the genital organ of the wearer, so as to enable it to support said organ, supplementing both its penetrative power and its caliber, while leaving its surface exposed for contact with walls of the vaginal duct during copulation, with the exception of the relatively small portion of the under side of said surface which rests against said splint.

The completeness of penetration and adequacy of caliber thus afforded will secure to both parties the attainment of a degree of stimulation needful for effective copulation, and a sense of elation conductive to confidence and sympathetic mutual attraction.

If it is not desired to provide for the attachment of the splint A to the member B after said member has been adjusted in position,—but, instead, to simultaneously apply said splint and member,—the detachable

means may be dispensed with; the splint being, in such case, permanently secured to said member.

The piece 35 may likewise be dispensed with, should it be deemed that adjustability of the size of the opening through the member B will not be required; the splint A being, in such a case, secured directly to the body 33.

In any event,—best results will be obtained by making attachment to the core 21, rather than to the material 22, in arranging the connection between the splint A and the member B.

Although the splint shown and hereinbefore described in detail is of such form as to materially supplement the caliber of a male genital organ, it should be understood that other features of this invention may be advantageously embodied in a splint of such form as to be suited for supporting such an organ without materially supplementing the caliber thereof.

It will be apparent to those skilled in this art that other changes may be made in the construction illustratively shown by the annexed drawing and hereinbefore described in detail, without departing from the spirit of this invention; what I therefore claim and desire to secure by Letters Patent of the United States of America is:

1. In a surgical appliance,—a splint for supporting a male genital organ during copulation, an annular member of form such as to enable it to suitably embrace such an organ near the base thereof, a piece associated with said member adjustable for varying the effective size of the orifice therethrough, means for locking said piece against changes in such adjustment, detachably interlocking tenons carried by said splint and piece, respectively, and a latch for securing said tenons in engaging relation.

2. In a surgical appliance,—a splint for supporting a male genital organ during copulation, an annular member of form such as to enable it to suitably embrace such an organ near the base thereof, a piece associated with said member adjustable for varying the effective size of the orifice therethrough, means for locking said piece against changes in such adjustment, and detachably interlocking tenons carried by said splint and piece, respectively.

3. In a surgical appliance,—a splint the outer portion of which is of soft elastic material, said splint having form and rigidity such as to enable it to suitably support a male genital organ during copulation, an annular member of form such as to enable it to suitably embrace such an organ near the base thereof, detachably interlocking tenons carried by said splint and member, respectively, and a latch for securing said

tenons in engaging relation; said latch enclosed within said splint and said splint and member so relatively formed that said tenons will be effectively enclosed during engagement thereof.

4. In a surgical appliance,—a splint the outer portion of which is of soft elastic material, said splint having form and rigidity such as to enable it to suitably support a male genital organ during copulation, an annular member of form such as to enable it to suitably embrace such an organ near the base thereof, detachably interlocking tenons carried by said splint and member, respectively, and a latch for securing said tenons in engaging relation; said latch enclosed within said splint.

5. In a surgical appliance,—a splint for supporting a male genital organ during copulation, an annular member of form such as to enable it to suitably embrace such an organ near the base thereof, detachably interlocking tenons carried by said splint and member, respectively, and a latch for securing said tenons in engaging relation.

6. In a surgical appliance,—a splint for supporting a male genital organ during copulation, an annular member of form such as to enable it to suitably embrace such an organ near the base thereof, and detachably interlocking tenons carried by said splint and member, respectively; said splint and member so relatively formed that said tenons will be effectively enclosed during engagement thereof.

7. In a surgical appliance,—a splint for supporting a male genital organ during copulation, an annular member of form such as to enable it to suitably embrace such an organ near the base thereof, a piece associated with said member for movement transversely of the orifice therethrough, and

means for detachably securing said splint to said piece.

8. In a surgical appliance,—a splint for supporting a male genital organ during copulation, an annular member of form such as to enable it to suitably embrace such an organ near the base thereof, a piece associated with said member for movement transversely of the orifice therethrough, and means for securing said splint to said piece.

9. In a surgical appliance,—a splint the outer portion of which is of soft elastic material and the inner portion of which comprises material having form and rigidity such as to enable said splint to suitably support a male genital organ during copulation, a non-hygroscopic envelope for said splint, an annular supporting member for said splint, and means for detachably securing said splint to said member in suitable relation; relative formation of said splint and member such that said means will be suitably enclosed by the material of the outer portion of said splint when secured to said member.

10. In a surgical appliance,—a splint the outer portion of which is of soft elastic material and the inner portion of which comprises material having form and rigidity such as to enable said splint to suitably support a male genital organ during copulation, an annular supporting member for said splint, and means for detachably securing said splint to said member in suitable relation, relative formation of said splint and member such that said means will be suitably enclosed by the material of the outer portion of said splint when secured to said member.

In witness whereof, I hereunto subscribe my name, this 1st day of July, 1922.

JEAN H. MARSHALL.
